COMBINED BOWL AND TRAY

James B. Swett, Barrington, R.I., assignor to Rexall Drug and Chemical Company, Los Angeles, Calif., a company of Delaware

Filed July 7, 1961, Ser. No. 65,845

Term of patent 14 years

(Cl. D44—10)

FIG. 3.

FIG. 5.

FIG. 4.

FIG. 1 is a top plan view of a combined bowl and tray, showing my new design;

FIG. 2 is a side elevation of the same;

FIG. 3 is a view in perspective of the same;

FIG. 4 is a bottom plan view of the same.

FIGURE 5 is a cross-section taken on line 5—5 of FIGURE 2.

The characteristic feature of the design resides in the appearance resulting from the interfitting of the separate bowl and tray with bases as shown.

I claim:

The ornamental design for a combined bowl and tray, as shown and described.
